DESIGN FOR A SELECTIVE INDEX OR SIMILAR ARTICLE

Robert Henderson, Summit, N. J.

Application September 16, 1947, Serial No. 141,425

Term of patent 14 years

(Cl. D74—5)

To all whom it may concern:

Be it known that I, Robert Henderson, a citizen of the United States of America, residing at Summit, in the county of Union and State of New Jersey, have invented a new, original, and ornamental Design for a Selective Index or Similar Article, of which the following is a specification, reference being had to the accompanying drawing, forming part thereof.

The figure is a perspective view of a selective index or similar article showing my new design. The side not shown is substantially like the one shown; and the back portion not shown is substantially plain.

I claim:

The ornamental design for a selective index or similar article, substantially as shown and described.

ROBERT HENDERSON.
